EXCAVATOR BUCKET

Ralph C. Kelsey, Cleveland, Ohio, assignor to The
Cleveland Trencher Company, Cleveland, Ohio,
a corporation of Ohio

Application October 26, 1946, Serial No. 705,967

5 Claims. (Cl. 37—91)

1

This invention relates to an improved excavating bucket and more particularly to an improved excavating bucket for a wheel-type excavating machine wherein the excavating or digging wheel comprises a pair of spaced rings, on the periphery of which the excavating buckets are mounted. These, therefore, are the general objects of the present invention.

An object of this invention is to provide an excavating bucket which may be easily detached from the digging wheel and which, when attached to the wheel, will become rigid therewith.

A further object of the present invention is to provide an excavating bucket for attachment to a wheel-type excavating machine, which bucket will insure the excavating of a trench of sufficient width to protect the fastening devices used to secure the excavating bucket in place on the wheel.

Other objects and advantages of the invention will become more apparent from the following description which refers to a preferred embodiment of the invention illustrated in the accompanying drawings. The essential features of the invention will be summarized in the claims.

In the drawings, Fig. 1 is a diagrammatic illustration of a wheel-type excavating machine having my improved excavating buckets mounted thereon; Fig. 2 is a side elevation, on an enlarged scale, of an excavating bucket and a fragment of the excavating wheel; Fig. 3 is a front elevation of the excavating bucket; Fig. 4 is a vertical section, the plane of which is indicated by the lines 4—4 on Fig. 3; Fig. 5 is a vertical section similar to Fig. 4 but illustrating the solid back member removed; Fig. 6 is a horizontal section as indicated by the line 6—6 on Fig. 3; Figs. 7, 8 and 9 are sectional details as indicated by the correspondingly numbered lines on Fig. 6; Fig. 10 is a sectional detail, the plane of the section being indicated by the lines 10—10 on Fig. 3; and Fig. 11 is a perspective view of the bucket attached to a digging wheel.

The excavating buckets, with which this invention is particularly concerned, are mounted on excavators of the wheel type, such as that generally indicated in Fig. 1. Such excavators may comprise a frame 10 mounted on crawlers 11. A motor 12 is mounted on one end of the frame 11 and an excavating wheel 14 is mounted on the other end thereof. The excavating wheel 14 is generally supported by a boom or frame member 15 which is pivotally and slidably mounted on a mast 16 carried by the frame 10. The wheel 14 may be raised and lowered on the mast 16 to determine the depth of cut by the operation of a hoisting mechanism which is connected to the boom 15 by cables 17. The motor 12 is connected with the hoisting mechanism and the crawlers 11 in the usual manner.

2

The excavating wheel 14 comprises a pair of rings 20 which are mounted in a spaced, parallel relation on the boom 15 as, for instance, by suitable rollers one of which is indicated at 18 in Fig. 1. Each ring 20 is provided with a series of pins or teeth 21 which are engaged by a suitable sprocket diagrammatically included in Fig. 1 at 19 and which is driven by the motor 12 to cause the excavating wheel to be rotated in the direction of the arrow shown in Fig. 1.

The excavator buckets 25 with which this invention is particularly concerned are scoop shaped and each bucket comprises a substantially U-shaped body portion 26 having an outwardly flaring forward lip portion 27. The body and lip portions of the bucket are made of metal of substantially the same thickness as that of the wheel rings 20. The edges 28 of the buckets are shaped to fit the peripheries of the wheel rings. Accordingly, the inner and outer surfaces of the bucket body form a continuation of the surfaces of the wheel rings and provide a smooth continuous surface so that when the bucket is moved to an inverted position (shown in Figs. 2, 3, and 4), excavated material may readily drop therefrom by gravity.

The forward, outwardly flaring lip portion 27 of each bucket may be provided with a plurality of removable rooter members 30. These rooters are bolted to the outer surface of the bucket by bolts 31. As shown in Figure 10 the lip portion 27 of the bucket 25 is provided with a plurality of openings 32 which extend through the lip and increase in cross sectional area as they approach the inner surface of the bucket. These openings are preferably square in cross section and receive the heads 33 of the bolts 31 to retain them in position and prevent turning thereof.

The bucket back may comprise a series of spaced rods or tines 35. These tines are preferably removably mounted in socket members 36 which are secured to the body portion 26 of the bucket as by welds 37. The rods 35 are secured in the socket by bolts 38. The rods or tines 35 are preferably of such length as will project from the wall of the bucket into the space between the wheel rings 20. The walls of the rings thus supplement the walls of the bucket and increase the capacity thereof.

Each bucket 25 is secured to the wheel rings 20 by a pair of elongated plates or bars 40. The bars 40 are applied to the outer face of the bucket body 26 and extend diagonally thereacross so that the upper surface 41 of each bar underlies and abuts the lower edge 42 of the outwardly flaring lip portion 27 of the bucket. The bars 40 are secured to the bucket body by welds 43, and to the lower edge of the outwardly flaring lip portion 27 by welds 44. Each bar 40 is of sufficient width to extend downwardly and engage

the outer face of its respective wheel ring 20. The bars are secured to the rings 20 by bolts 45. The portion 27 of the bucket flares outwardly a distance sufficient to insure the excavation of a trench of sufficient width to provide clearance 5 for the bolts 45. This protects the bolts and facilitates replacement of the bucket. The welding of the flange or lip portion 27 to the bars 40 provides an especially rigid structure which maintains the forward portion of the bucket at 10 its maximum width by preventing the collapse thereof, thus insuring protection of the bolts over prolonged periods of use.

When the bucket is used in loose earth, a solid back 50 may be provided. This back comprises a metallic plate shaped to fit between the wall of the bucket and the rings 20. The plate 50 is provided with a pair of flanges 51 which are secured to the respective rings 20 by bolts 52 while the upper end of the plate (Figs. 3 and 4) rests in a 15 seat formed by the socket members 36 and lugs 54 which are secured to the bucket as, for instance, by welds 55. In the drawings I have shown one lug 54, but a plurality of such lugs may be used if desired.

From the foregoing specification it will be seen that I have provided a rigid excavating bucket which is particularly adapted for use in connection with rotating digging wheels and which is adapted to be readily replaced, thus increasing the life of the digging wheel. The improved bucket is so constructed as to facilitate the use of a solid back plate without interfering with other parts of the bucket and without attachment to the bucket itself.

The flaring of the forward edge of the bucket and the reenforcement of the flaring portion adjacent the side of the bucket by the welding of the attaching plate thereto results in an exceedingly rigid structure having a minimum weight. The flaring of the bucket insures the excavation of a trench of sufficient width to provide clearance, not only for the heads of the bolts which attach the bucket to the digging wheel, but also for the pins or teeth-like formation of the 45 wheel which coat with the driving gear to rotate the wheel.

I claim:

1. An excavating bucket for an excavating wheel having a pair of spaced annular rings, said bucket comprising a U-shaped body portion adapted to be mounted in edge relation with the wheel ring to space the rings and provide a smooth and continuous inner and outer surface, said body portion being provided with a forward portion flaring outwardly beyond the outer faces of the rings, an elongated bar applied to the meeting edges of the body portion and each ring on the outer surfaces thereof and extending diagonally relative to such meeting edge, the forward portion of the bar underlying the edges of the outwardly flaring portion of the bucket, said bar being secured to the outer face of the body portion, and to the lower edge of the outwardly flaring portion of the bucket.

2. An excavating bucket for an excavating wheel having a pair of spaced annular rings, said bucket comprising a substantially U-shaped body portion the legs of which are adapted to be mounted in edge relation with the wheel rings to thereby provide a continuation of inner and outer surfaces of such rings, the legs of said body portion each being provided with a forward portion

flaring outwardly beyond the outer faces of the rings, an elongated bar applied to the meeting edges of and overlying the body portion and each ring and extending diagonally relative to such meeting edge, the forward portion of the bar underlying the edges of the outwardly flaring portions, said bar being welded to the outer face of the body portion, and a weld for uniting the upper edge of the bar to the lower edge of the outwardly flaring portions of the bucket.

3. An excavating bucket for an excavating wheel having a pair of spaced annular rings, said bucket comprising a U-shaped body portion, the legs of which are arranged and adapted to be mounted edge to edge with respective wheel rings to provide smooth and continuous inner and outer surfaces therewith, said body portion being provided with a forwardly and outwardly flaring integral lip portion, an elongated bar applied to the meeting edges of the bucket and the ring and extending diagonally relative to the meeting edge, said bar overlying the body portion of the bucket and underlying the edge of the outwardly flaring portion thereof, a weld for securing the bar to the body portion and to the outwardly flaring portion, bolts extending through said bar for securing the bucket to the rings and wherein said outwardly flaring portion extends outwardly beyond the bar a distance substantially equal to the thickness of the metal to thereby prevent collapsing of the flaring portion of the bucket in regions adjacent the ring and thus insure the cutting of a trench of a predetermined width.

4. An excavating bucket for an excavating wheel having a pair of spaced annular rings, said bucket comprising a U-shaped body portion adapted to be mounted in edge relation with the wheel ring to space the rings and provide a smooth and continuous inner and outer surface therewith, said body portion being provided with a forward portion flaring outwardly beyond the outer faces of the rings, an elongated bar applied to the meeting edges of the body portion and each ring and extending diagonally relative to such meeting edge, the forward portion of the bar underlying the edges of the outwardly flaring portion of the bucket, said bar being secured to the outer face of the body portion, and to the lower edge of the outwardly flaring portion of the bucket, a series of spaced tines secured to the body portion adjacent its rearmost edge and extending upwardly into said seat and downwardly into the space between the rings, a lug secured to the body portion and spaced forwardly of one of said tines and forming a seat therebetween, a back plate for said bucket extending between the walls thereof and between said rings, flanges on said plate, and means to secure said flanges to said rings.

5. In an excavator bucket a U-shaped body portion the legs of which are adapted to be secured to the spaced rings of an excavator wheel, a series of spaced tines secured to the bucket adjacent the rear edge thereof and extending downward into the space between said rings, a lug secured to said bucket and extending inwardly to coat with one of said tines to form a seat therewith, a solid back plate for said bucket adapted to project into said seat and extend into the space between said rings, and means to secure the lower edge of said plate to respective rings.

RALPH C. KELSEY.
